Primary Examiner — Rosemary K Tarcza*Assistant Examiner* — Nathaniel D Buckner(74) *Attorney, Agent, or Firm* — Condo Roccia Koptiw LLP**CLAIM**

The ornamental design for a wireless charging fixture, as shown and described.

DESCRIPTION

FIG. 1 is a first perspective view of a wireless charging fixture embodying my new design;

FIG. 2 is a second perspective view of the wireless charging fixture of FIG. 1;

FIG. 3 is a top view of the wireless charging fixture of FIG. 1;

FIG. 4 is a first side view of the wireless charging fixture of FIG. 1;

FIG. 5 is a bottom view of the wireless charging fixture of FIG. 1;

FIG. 6 is a second side view of the wireless charging fixture of FIG. 1;

FIG. 7 is a third side view of the wireless charging fixture of FIG. 1; and,

FIG. 8 is a fourth side view of the wireless charging fixture of FIG. 1.

The broken lines in the figures represent portions of the article which form no part of the claim.
